(57) CLAIM

The ornamental design for a package for a feminine hygiene product, as shown and described.

DESCRIPTION

FIG. 1 is a front perspective view of a package for a feminine hygiene product showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines surrounding the front side and surrounding the rear side of the package for a feminine hygiene product are the boundaries to the claim and form no part thereof. The top, bottom, right and left sides of the article and the broken lines are not included in the claim.
